COMBINED CLOTHES SUPPORT ROD AND MOUNTING BRACKETS THEREFOR

William L. Borgeld, Wyoming, Mich., assignor to The Leslie Metal Arts Co., Inc., Grand Rapids, Mich.

Filed May 6, 1968, Ser. No. 11,789

Term of patent 14 years

Int. Cl. D6—01

U.S. Cl. D33—8

Fig. 1

Fig. 2

Fig. 3

FIG. 1 is a perspective view of a combined clothes support rod and mounting brackets therefor showing my new design;

FIG. 2 is a view showing the rod members telescoped together and one mounting bracket separated from the rod; and

FIG. 3 is a side elevational view with portions of the design being broken away for convenience of illustration.

The configuration of the brackets at the opposite ends of the rods is the same, except for the difference in the diameter of the openings receiving the telescoping rod sections.

I claim:

The ornamental design for a combined clothes support rod and mounting brackets therefor, as shown and described.
